Raymond J. Lohr, Erie, Pa., assignor to Louis Marx & Company, Inc., New York, N.Y., a corporation of New York

Application April 28, 1959, Serial No. 55,685

Term of patent 14 years

(Cl. D34—15)

Fig. 4.

Fig. 5.

Fig. 6.

Fig. 1 is a perspective view of a table tennis practice device embodying features of my invention;

Fig. 2 is an enlarged end view thereof;

Fig. 3 is an enlarged front elevation thereof;

Fig. 4 is an enlarged plan view thereof;

Fig. 5 is an enlarged bottom view thereof; and

Fig. 6 is an end view looking at the end remote from that shown in Fig. 2.

The intersecting cords of the front and back nets are shown in fragmentary areas, it being understood that the nets are complete.

I claim:

The ornamental design for a table tennis practice device, substantially as shown and described.
